(57) **CLAIM**

The ornamental design for pegboard module and assembly thereof, as shown and described.

DESCRIPTION

FIG. 1 is a front perspective view of a pegboard module according to the present invention;

FIG. 2 is a rear perspective view of the pegboard module of FIG. 1;

FIG. 3 is a top plan view of the pegboard module of FIG. 1;

FIG. 4 is a front elevated view of the pegboard module of FIG. 1;

FIG. 5 is a rear elevated view of the pegboard module of FIG. 1;

FIG. 6 is a bottom plan view of the pegboard module of FIG. 1;

FIG. 7 is a right side elevation view of the pegboard module of FIG. 1; and,

FIG. 8 is a left side elevation view of the pegboard module of FIG. 1.
